WOOD SAWING MACHINE AND POWER TAKE-OFF DEVICE

Filed May 15, 1928

UNITED STATES PATENT OFFICE

WILLIAM N. SEVERANCE, OF DALEVILLE, MISSISSIPPI, ASSIGNOR OF FIVE-EIGHTHHS TO
JOHN S. WARREN, OF SUN, MISSISSIPPI

WOOD SAWING MACHINE AND POWER TAKE OFF DEVICE

Application filed May 15, 1928. Serial No. 277,881.

My invention relates to an improved wood sawing machine of the circular saw type and also to an improved form of device adapted to take off power from a drive wheel of a motor vehicle and transmit it to my saw or to other machines.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views:—

Fig. 1 is a front elevation of a wood sawing machine, the same being connected in driving relation to a wheel of a motor vehicle by means of my improved power take-off;

Fig. 2, an end view of Fig. 1; and

Fig. 3 a perspective view of my improved power take-off.

Referring now to the drawings in detail, it will be observed that my improved sawing machine includes essentially a main frame A composed of a pair of base members 10, 10, connected together in parallel, spaced relation by two or more transverse members 12, 12 and having rigidly secured thereto and rising therefrom, intermediate their ends, respectively, a pair of uprights or standards 14, 14.

Bearings are carried by the standards 14, 14, respectively, and in said bearings is journaled for rotation a horizontal shaft 18, having detachably mounted on one end thereof a circular saw 20. A swinging work support indicated generally at B serves to move material to and from the saw 20.

My improved power take off device as illustrated in detail in Figs. 1, and 3 of the drawings consists essentially of adjustable means for connection with motor vehicle wheels of different sizes and constructions and a shaft connected with said adjustable means for transmitting rotary movement of the latter to the drive shaft 18 of my sawing machine or to the drive shaft of any other machine, such as a cream separator, corn

sheller, grinding mill, pump, lathe or the like, irrespective of whether or not such drive shaft is axially alined with the wheel of the motor vehicle. Said adjustable means is inclusive of a spider member 84 and a cap member 86, while said shaft, 88, is inclusive of a pair of universal joints 90, 90 at the ends thereof, one of which is connected with the cap member 86 and the other of which is adapted for connection with the shaft to be driven, such, for example, as shaft 18 of my wood sawing machine.

The spider member 84 consists of a ring 92 provided with a circular series of bolt receiving apertures 94 and having radiating therefrom a plurality of arms 96 each provided with a longitudinal slot 98, while the cap member 86 which is of size to fit over the hub cap of a vehicle wheel, is closed at its outer end and there suitably formed for connection with one of the universal joints 90, and at its inner open end is provided with an outwardly directed flange 100 corresponding in size to and apertured as at 102 the same as the ring 92 of the spider member 84, whereby said spider member and said cap are adapted for detachable connection with one another by bolts passed through alined apertures 94—102 as indicated in Fig. 1 of the drawings.

Associated with each spider arm 96 is an arm extension member 104, longitudinally slotted as at 106, provided at its outer end with a bolt receiving aperture 108, and bent at right angles upon itself and formed into a T-shape at its inner end as indicated at 110. The extension members 104 are positioned against either the inner or the outer faces of their related spider arms 96 and bolts 112 are passed through the slots 98—106 in said arms and members, respectively, to secure them together in any relatively adjusted position permitted by said slots, the T-shaped formations 110 at the inner ends of the extension members being adapted for cooperation with the faces of the arms 96 opposite to the faces against which the members 104 are positioned, either by being passed through the slots 98 in the spider arms or by being engaged over marginal edge portions

of said arms, as indicated in Fig. 3 to assist the bolts 112 in maintaining said extension members rigidly connected with their related arms in any adjusted position of said members with respect to said arms, it being noted in this respect that not only may the effective length of the spider arms constituted by the arms themselves and the extension members 104 be increased or lessened, but that the distance between the aperture 108 in any given arm and the aperture 108 in any adjacent arm may also be increased or lessened as desired whereby the apertures in all of the members 104 may be brought into alinement with the usual rim lug retaining bolts of vehicle wheels of different sizes.

In the use of my power take off device the vehicle with which it is to be connected is first jacked up or otherwise elevated sufficiently to raise the wheel thereof from which power is to be derived out of engagement with the ground, either the jack or other means employed for raising the vehicle, or any suitable support such as is indicated at 114 in Fig. 1, being employed to maintain said wheel in an elevated position. The extension members 104, if not previously adjusted, then are adjusted relatively to their related spider arms, so that the apertures 108 therein will aline with the lug bolts of the wheel, provided, of course, the wheel is of a type including lug bolts. The usual lug bolts nuts then are removed and said extension members engaged over said lug bolts and the nuts again applied to secure the spider to the wheel, the cap member 86 having previously been connected with the spider ring 92 by means of bolts passed through alined apertures 94—102 in said ring and the cap flange 100 as is understood. The shaft 88 then is connected with the shaft 18 or other shaft to be operated thereby, whereupon rotation of the vehicle wheel will impart rotation to said shaft irrespective of whether said wheel and shaft are or are not axially alined as is obvious.

In some instances it may be possible to disconnect the cap member 86 from the spider member 84 and connect the cap member directly with a vehicle wheel by bolts passed through the apertures 102 in the flange 100 of said cap member.

Furthermore, if desired, a pulley (not shown) may be mounted on the cap member 86 to establish a belt drive between a vehicle wheel and any desired article of machinery.

I claim:—

1. A power take off device for connecting an article of machinery with a drive wheel of a motor vehicle comprising a spider member, said spider member consisting of an apertured ring, slotted arms radiating therefrom, a slotted arm extension member positioned against one face of each arm, a bolt

connecting each arm with its related extension member, a T-shaped formation on the inner end of each extension member engageable with its related arm to assist said bolts in securing said extension members to their related arms, said extension members being apertured to receive bolts carried by the wheel from which power is to be derived, and means for establishing a driving connection between said spider member and a device to be driven by said wheel.

2. A power take off device for connecting an article of machinery with a drive wheel of a motor vehicle comprising a spider member and a cap, said spider member including an apertured ring, means for securing said ring to a wheel of a motor vehicle, a flange on said cap member having apertures adapted for alinement with the apertures in said ring, bolts adapted to be passed through said apertures to detachably connect said spider member and cap together, said cap when detached from said spider member being adapted to have wheel carried bolts passed through the apertures on the flange thereof to connect said cap directly with a wheel, and a shaft having a universal joint at each end thereof, one of which is connected with said cap and the other of which is adapted for connection with a shaft to be driven from a wheel with which said cap is connected.

In testimony whereof I hereunto affix my signature.

WILLIAM N. SEVERANCE.
